UNITED STATES PATENT OFFICE.

FRANK E. WATERMAN, OF PARKERSBURG, WEST VIRGINIA, ASSIGNOR OF ONE-HALF TO JAMES A. WETHERELL, OF SAME PLACE.

DESIGN FOR A BADGE OR SIMILAR ARTICLE.

SPECIFICATION forming part of Design No. 26,101, dated September 29, 1896.

Application filed August 17, 1896. Serial No. 603,085. Term of patent 3½ years.

To all whom it may concern:

Be it known that I, FRANK E. WATERMAN, a citizen of the United States, residing at Parkersburg, in the county of Wood and State of West Virginia, have invented or produced a new and useful Design for a Campaign-Badge or Similar Article, of which the following is a specification.

My design consists in a campaign badge, ribbon, or banner; and the leading features thereof reside in the pictorial representation of the head of a man, a crown of thorns, and a cross.

The design is illustrated in the accompanying drawing, in which the figure is the face view of a badge, ribbon, or banner.

In the said drawing the reference-numeral 1 indicates the body of the badge, ribbon, or banner; 2, the pictorial representation of the head of a man, which in practice will of course be that of the candidate. Above the head of the man is provided a panel or space 3, intended for the reception of suitable words,

and immediately beneath the pictorial head is another panel or space 4 for the reception 25 of other suitable words.

The numeral 5 indicates the crown having a wreath of thorns 6, above which is a panel or space 7, adapted for the reception of a suitable word.

The numeral 8 represents a cross, which in the article will be of gold, and above which is a panel or space 9, adapted to contain a suitable word.

My design presents a handsome, attractive, 35 and distinctive badge, ribbon, or banner.

What I claim is—

The design for a badge, or similar article, herein shown and described.

In testimony whereof I have hereunto set 40 my hand in presence of two subscribing witnesses.

FRANK E. WATERMAN.
